UNITED STATES PATENT OFFICE

2,445,369

HYDRAULIC TRANSMISSION FOR
OUTBOARD MOTORSSamuel F. Shields, McDavid, Fla., assignor of
one-half to Paul M. Clyde, Pensacola, Fla.

Application January 22, 1942, Serial No. 427,800.

2 Claims. (Cl. 60—53)

1

This invention relates to a novel construction of outboard motor and more particularly to a motor provided with a hydraulic transmission and including an arrangement of valves and conduits to enable the propeller shaft of the motor to be driven in either direction.

Another aim of the invention is to provide a hydraulic transmission of simple construction for use with outboard motors and which will enable the propeller shaft to remain idle while the engine or prime mover of the outboard motor is in operation to provide a neutral position between the engine and propeller shaft.

A further aim of the invention is to provide a transmission capable of being controlled by a pivotally mounted lever connected to the steering arm of the motor.

Still another aim of the invention is to provide automatic means for automatically reducing the speed at which the prime mover or engine is operated when the transmission is in a neutral position and which is so arranged in conjunction with the means for controlling the transmission, that the speed at which the propeller shaft is driven will vary proportionately to the speed at which the engine is driven.

Other objects and advantages of the invention will hereinafter become more fully apparent from the following description of the drawings, which illustrate a preferred embodiment thereof, and wherein:

Figure 1 is a side elevational view showing an outboard motor constructed in accordance with the invention.

Figure 2 is an enlarged side elevational view showing the hydraulic transmission removed.

Figure 3 is an enlarged rear elevational view of the transmission.

Fig. 4 is an enlarged vertical sectional view taken substantially along the plane of the line 4—4 of Figure 3.

Figure 5 is a transverse sectional view of the rotor and rotor casing taken substantially along a plane as indicated by the line 5—5 of Figure 4.

Figure 6 is an enlarged vertical sectional view taken substantially along the plane of the line 6—6 of Figure 2.

Figure 7 is an enlarged horizontal sectional view taken substantially along the plane of the line 7—7 of Figure 2, and

Figures 8, 9 and 10 are enlarged horizontal sectional views taken substantially along the planes of the lines 8—8, 9—9 and 10—10, respectively, of Figure 3.

Referring more particularly to the drawings,

wherein like reference characters designate like or corresponding parts throughout the different views; 12 designates generally an outboard motor constructed in accordance with the invention and which includes a tubular column 13 having a propeller skeg 14 at the lower end thereof and a motor casing 15 mounted on its upper end and which is adapted to contain a prime mover or engine, not shown, of the outboard motor 12. A steering arm 16 projects forwardly from the column 13 adjacent its upper end. A collar 17 is turnably mounted on the column 13 just below the steering arm 16 and is provided with a forwardly projecting arm 18. A clamp 19 has an upwardly projecting shank 20 which is pivotally connected at 21 to the free end of the arm 18. The clamp 19 is adapted to be connected in a conventional manner to the stern of a boat for mounting the outboard motor 12 thereon and is provided with a rearwardly extending outwardly bowed portion 22 having an arcuately arranged series of openings 23 for selectively receiving a stop pin 24 which is adapted to engage a flange 25 on the column 13 for limiting the swinging movement of the column toward the clamp 19. The flange 25 may also be provided with a series of apertures 23 in any one of which the stop pin 24 can be mounted for engaging the arcuately shaped edge of the clamp portion 22. A contractile coil spring 26 is fastened at its upper end to the inner portion of the arm 18 and at its lower end to the clamp 19 for urging the arm 18 and the collar 17 to swing downwardly on the pivot 21 for swinging the lower portion of the column 13 forwardly or in a direction toward the clamp 19.

A pump housing 26 is connected to and partly disposed in the column 13 beneath or adjacent the collar 17. The casing 26 is oval in cross section, as best seen in Figure 7, and contains two intermeshed pumping gears, 27 and 28. The gear 27 is keyed to a shaft 29 which extends upwardly therefrom through the upper part of the column 13 and into the engine casing 15 and which is adapted to be connected to or to form the driven shaft of the prime mover and which drives the gear 27 in a counter-clockwise direction, as seen in Figure 7. The gear 28 is mounted on a shaft 30, the ends of which are disposed in the casing 26 and said gear 28 forms an idler gear which is driven by the gear 27. The casing 26 is provided with oppositely disposed downwardly extending ports 31 and 32 which open into the casing 26 between the gears 27 and 28 and the ports 31 and 32 communicate

with fittings 33 and 34, respectively, which depend from the housing 26 and which are provided with conical shaped bores 35 and 36, respectively, which are tapered toward their lower ends. The fitting 33 is provided with oppositely opening ports 37 and 38 and the fitting 34 is provided with similar ports 39 and 40.

Bore 35 contains a conical shaped valve 41 having a restricted, closed lower end which closes the lower end of the bore 35 and an enlarged open upper end which communicates with the port 31. The closed lower end of the valve 41 is provided with an opening through which a shaft 42 extends which is keyed to the valve 41 and which has one end depending from the valve 41. A valve 43 is mounted in the bore 36. The valve 43 is identical with the valve 41 except that it is not provided with an opening in its restricted end but has a stub shaft 44 depending therefrom. The valve 41 is provided with two circumferentially elongated circumferentially spaced ports 45 and 46 intermediate of its ends which are movable into positions to register with the ports 37 and 38, respectively. The distance, circumferentially, between the remote ends of the ports 45 and 46 is less than an arc of one hundred and eighty degrees. As seen in Figure 10, the valve 43 is provided with a pair of similarly disposed ports 47 and 48 which are movable to positions to register with the ports 39 and 40, respectively.

As seen in Figure 1, the column 13 is provided with an enlargement 49 near the skeg 14 in which is disposed a rotor casing 50 provided with a chamber 51, as seen in Figures 4 and 5, in which is disposed a rotor 52, from one side of which projects a propeller shaft 53 which is journaled in the enlargement 49 and which projects outwardly from its rear end and has a propeller 54 keyed thereto. A stub shaft 55 projects from the opposite side of the rotor 52 and is journaled in the enlargement 49 for rotatably mounting the rotor in the chamber 51. The rotor 52 is provided with crossed diametrically extending slots 56 for containing crossed vanes 57 and 58. The vane 57, as seen in Figure 4, is formed of sections having extensions 59 projected from opposite edges thereof and forming an opening 60 in the center of the vane in which is slidably mounted a restricted shank 61 which forms the intermediate portion of the vane 58 to enable the vane to slide diametrically of the rotor 52 and relatively to one another. As seen in Figure 5, the vanes 57 and 58 are substantially longer than the slots 56. The chamber 51 includes an upper arcuately shaped portion which loosely engages the rotor 52 and a lower portion which is spaced from the rotor and which forms an arcuately shaped space 62 the length of which is greater than one hundred and eighty degrees. Consequently, when the rotor is revolved, the ends of the vanes 57 and 58 will engage the upper portion of the chamber 51 for forcing the opposite ends of the vanes outwardly against the outer side of the space or chamber 62. The rotor casing 50 is provided with integral conduits 63 and 64 which open into the ends of the space or chamber 62.

A pipe 65 is connected at one end to the conduit 63 and has its opposite end communicating with the port 37. A pipe 66 is connected at one end to the conduit 64 and has its opposite end communicating with the port 39. A branch pipe 67 is connected at one end to the fitting 33 and communicates with the port 38 and is connected at its opposite end to the pipe 66, intermediate

of the ends thereof. A branch pipe 68 communicates at one end with the port 40 and has its opposite end in communication with the pipe 65, intermediate of the ends thereof. The pipes 65, 66, 67 and 68 have their upper ends disposed exteriorly of the column 13 and their lower portions disposed therewithin and the fittings 33 and 34 are disposed on the outer side of the column 13.

10 Referring to Figure 6, the casing or housing 26 is provided with a port 69 in the top thereof directly above the port 31 and has a fitting 70 projecting upwardly therefrom and communicating therewith. The fitting 70 corresponds to the fittings 33 and 34 except that it is provided with a single outwardly opening port 71 intermediate of its ends which communicates with a conduit 72. Said conduit 72 has an end opening downwardly into a port 73 which is disposed directly above the port 32. A conical shaped valve 74 is turnably mounted in the fitting 70 and has an opening in its restricted end through which the upper end of the shaft 42 extends and in which said shaft is keyed. The valve 74, as best seen in Figure 8, is provided with a single circumferentially elongated opening 75 intermediate of its ends which is movable into and out of registry with the port 71. The upper end of the shaft 42 extends above the valve 74 and has keyed thereto 25 a crank arm 76. Corresponding crank arms 77 are keyed to the lower end of the shaft 42 and to the stub shaft 44. The crank arms 76 and 77 are urged toward headed ends of the shaft 42 and the stub shaft 44 by means of expansion 30 springs 78. The free ends of the crank arms 77 are pivotally connected to the ends of a link 79 so that the valves 41, 43 and 74 will turn as a unit when the crank arm 76 is actuated, as will hereinafter be explained.

40 As best seen in Figure 2, a cylinder 80 is mounted on the top of the pump housing 26 and is connected adjacent its lower end by a pipe 81 to the high pressure side of the pump housing 26. Cylinder 80 contains a piston 82 having a piston rod 83 which extends upwardly through the top thereof and which is slidably mounted therein. A coil spring 84 urges the piston 82 downwardly. A flexible shaft 85 is connected at its lower end to the upper end of the piston rod 83 and is connected at its upper end to a lever 86 which is adapted to be connected to a conventional control valve, not shown, of the prime mover, which is disposed in the casing 15, for regulating the flow of the fuel mixture thereto.

55 A lever 88 is pivotally mounted on the steering arm 16 and has its free end disposed beneath the handle portion thereof and is connected to a flexible shaft 89 and which shaft is connected to the free end of the crank arm 76. The flexible 60 shaft 89 includes a flexible conduit which is clamped to the steering arm 16, and to the pump housing 26, by a bracket 89.

Assuming that the engine or prime mover, within the casing 15, is driving the gear 27 in a 65 counterclockwise direction, as seen in Figure 7, and that the control lever 88 is in its position of Figure 1, with the control lever 88 thus disposed the valves 41, 43 and 74 will be in their positions as seen in Figures 9, 10 and 8, respectively. The 70 system, including the conduit pipes, which connect the rotor casing to the pump housing, and said housing and casing, is adapted to be filled with a hydraulic liquid. The rotation of the gears 27 and 28 will therefore draw the liquid inwardly 75 of the housing 26 through the port 32 and will

force the liquid outwardly through the ports 31 and 69. With the valves in the positions of Figures 8, 9 and 10, the liquid will be admitted to the intake fitting 34 through its port 33 and through the port 47 of the valve 43. A part of the liquid will be forced outwardly through the valve port 45 and the fitting port 37 into the conduit 65. The remainder of the liquid will pass upwardly through the ports 69, 75 and 71 and through the conduit 72 and the port 73 back to the intake side of the housing 26 so that this portion of the liquid will be by-passed around the pump from its pressure side to its suction side. The liquid which is forced into the conduit 65 is forced downwardly therethrough and through the conduit 63 into the chamber 62 to turn the rotor 52 in a counterclockwise direction, as seen in Figure 5. The blades of the propeller 54 are pitched so that when it is thus turned the motor 12 would drive in a forward direction. The fluid passes around the chamber 62 through conduit 64 and pipe 66, and through ports 39, 47 and 32 back to the intake side of the pump. The pressure of the liquid in the high pressure side of pump housing 26 will raise the piston 82 part way and partially open the valve for controlling the fuel feed to the engine so that the motor 12 will be driven at a low speed. By moving the control lever 88 further away from the steering arm 16, the valves 41, 43 and 74 will all be turned in counter-clockwise directions, as seen in Figures 8, 9 and 10, to fully expose the ports 45 and 47 and to close the port 75 so that none of the hydraulic fluid will be by-passed and all of it will be utilized by the rotor 52, in the same direction as previously described. This will cause the propeller 54 to be driven at a faster speed and will also increase the pressure on the underside of the piston 82, due to the fact that there will be as much pressure against the underside of piston 82 as against the rotor blades, so that the fuel control valve of the engine will be moved to a fully open position to cause the motor to drive at its full speed. By moving the control lever 88 upwardly to an intermediate position, the valves in Figures 8, 9 and 10 will be turned in clockwise directions for fully opening the port 75 and for closing both ports of the valves 41 and 43 so that all of the hydraulic liquid will be bypassed through the conduit 72. As a result, the propeller 54 will not be driven and the transmission will be in a neutral position. This will relieve substantially all pressure on the high pressure side of the pump, allowing the spring 84 to return the piston 82 to a fully retracted position for fully closing the fuel valve so that the engine will only receive sufficient fuel to permit it to idle. By moving the control lever 88 further toward the handle of the arm 16 the valves in Figures 8, 9 and 10 will be further moved in a clockwise direction to partly close the port 75 and to partly open the ports 46 and 48. When thus positioned, the valves will cause a portion of the hydraulic fluid to be by-passed and the remaining portion thereof will pass downwardly through port 31, ports 46 and 38, pipe 67 and the lower portion of pipe 66 and into the chamber 62 through the conduit 64 for driving the rotor 52 in a clockwise direction, as seen in Figure 5, to thereby cause the propeller to be driven in reverse so that the motor 12 will drive in reverse. The hydraulic liquid passes from the chamber 62 through conduit 63 and the lower portion of pipe 65, up through pipe 68 and ports 40 and 48 and

the intake port 32 back to the intake side of the pump. By moving the control lever 88 to a fully raised position the port 75 will be closed and the ports 46 and 48 fully opened so that all of the hydraulic fluid will be pumped through the rotor casing and so that the fuel control valve will be in a fully opened position.

When the motor 12 is driving in reverse, the spring 26 will prevent the column 13 from swinging upwardly and said spring also acts to yieldingly hold the column in its position of Figure 1 so that it can ride over any obstruction that it might strike.

The pipes 65 and 66 have excess pressure cylinders 90 connected thereto and which contain air. Should the rotation of the propeller 54 be obstructed and during the movement of the valves to open and closed positions, any excess pressure built up in the system will be forced into the cylinders 90 to thereby relieve the pressure on the system.

The engine contained in the casing 15 is not shown and described as it forms no part of the invention and any suitable type of internal combustion engine capable of driving the shaft 29 may be used.

Various modifications and changes are contemplated and may obviously be resorted to, provided they fall within the spirit and scope of the invention as hereinafter defined by the appended claims, as only a preferred embodiment thereof has been disclosed.

I claim as my invention:

1. A hydraulic transmission comprising a pump mechanism having a housing containing a fluid, depending valves on said housing, a conduit from one of the valves to the outlet side of the pump housing, a conduit from the other valve to the inlet side of the pump housing, a rotor provided with a casing, a main pipe connecting the valve, associated with the outlet side of the pump housing, to one side of the rotor casing, a second main pipe connecting the other valve to the opposite side of the rotor casing, branch pipes leading from the valves and crossing and communicating with the opposed main pipes, said pipes forming the sole support of the rotor, one of the conduits and the main pipe associated therewith conveying the pumped fluid to the rotor casing to drive the rotor and the other main pipe and associated conduit returning the fluid to the pump housing, and means by which said valves are operable as a unit to divert the flow of the fluid through the branch pipes for reversing the direction of movement of the fluid in the rotor.

2. A hydraulic transmission comprising a pump mechanism having a housing containing a pump fluid, said housing having an outlet port and an inlet port connected to the outlet and inlet sides, respectively, of the pump, valves mounted in said ports, a rotor including a casing, a conduit leading from one side of the rotor casing to one side of the outlet port, a second conduit leading from the other side of the rotor casing to one side of the inlet port, branch conduits extending from the first and second mentioned conduits and crossing one another and connecting respectively with the opposite sides of inlet and outlet ports, said conduits forming the sole support of the rotor, and operating means for operating said valves as a unit whereby when the valves are in one position the fluid will pass to and from the pump housing and rotor casing through the first and second mentioned conduits only and when

in an alternate position the fluid will be diverted through the branch conduits for reversing the direction of flow thereof in the rotor casing and in the first and second mentioned conduits.
